UNITED STATES PATENT OFFICE.

ARTHUR F. CASE, OF CLEVELAND, OHIO, ASSIGNOR TO THE WELLMAN-SEAVER-MORGAN COMPANY, OF CLEVELAND, OHIO, A CORPORATION OF OHIO.

ROTARY CAR DUMPER.

Application filed January 11, 1924. Serial No. 685,504.

To all whom it may concern:

Be it known that I, ARTHUR F. CASE, a citizen of the United States, residing at Cleveland, in the county of Cuyahoga and 5 State of Ohio, have invented a certain new and useful Improvement in Rotary Car Dumpers, of which the following is a full clear, and exact description.

This invention relates to rotary car dumpers of the general type illustrated in Patent 10 No. 1,407,926, granted in my name on the 28th day of February, 1922, and also in my pending application Serial No. 682,144, filed December 22, 1923.

15 A dumper of the type referred to, includes a rotary cradle with a car supporting portion including preferably a platen which has a lateral motion when the rotating movement begins to allow one side of the car to be supported during the dumping motion, and includes also supporting rings engaging rollers on which the cradle as a whole turns under the actuation of motor driven pinions which engage arc-shaped racks, and additionally 20 it includes car clamps which hold the car on the platen while the cradle is being rotated to dumping position and back again, these car clamps being preferably actuated by weights. What may be termed the 25 dumping side of the cradle has an apron plate or dumping plate over which the coal or other contents of the car flows in the dumping operation.

It has been found that under certain 30 conditions the discharge of coal from the cars is not entirely satisfactory when a car of substantially the length of the cradle is being dumped, particularly if the car is of low or medium height. Under such conditions it 35 has been found that when the cradle is being turned, the coal (for convenience the contents will be assumed to be coal) flows out of the top of the car onto the apron plate or dumping plate, and in seeking its natural

40 angle of repose it not only flows forwardly on the apron plate but also in an endwise direction beyond the ends of the car with the result that when the cradle reaches a given position, say about a 90° position, the coal 45 flows off the ends of the apron plate or out of the ends of the cradle onto the foundation, and clogs the space at the ends of the cradle necessitating its removal by digging it out. There is a further disadvantage also in the 50 manner in which the coal piles up in the hop-

pers beneath the cradle. It was found that due to the fact that the coal was spread lengthwise of the apron plate for a distance somewhat greater than the length of the car, when the coal flows into the hoppers there 60 was an uneven distribution of coal at the top, the coal piling up higher in the ends of the hoppers than at the middle.

I obviate these difficulties preferably by 65 obtaining a partial dumping of the coal at or from the ends of the car while the cradle is being turned and before the coal from the middle portion of the car begins to slide over the forward edge of the apron, and this I accomplish in this instance by a specially 70 constructed apron which permits the relatively early discharge of coal into the hoppers from the end portions of the car without piling up or accumulating on the apron plate. In the particular embodiment of the 75 invention herein illustrated the apron plate is provided with two discharge openings located near opposite ends and near the ends of a car of maximum length so that while the cradle is being turned, the coal which 80 would ordinarily pile up on the ends of the apron plate passes through these openings into the hoppers, this coal lodging in the bottom of the hoppers. Then when the cradle is rotated further, the rest of the coal passes 85 in the usual manner over the forward edge of the apron plate into the hoppers with the result that there is no spillage of the coal over the ends of the apron plate or from the ends of the cradle as was experienced heretofore, and when the car has been dumped there is a substantially uniform distribution 90 of coal in the hoppers.

The invention may be further briefly summarized as consisting in certain novel details of construction, and combinations and arrangements of parts which will be described in the specification and pointed out in the appended claims.

100 In the accompanying sheets of drawings, wherein I have illustrated the preferred embodiment of the invention, and with the parts of the cradle shown somewhat conventionally, for the sake of clearness, Fig. 1 is a vertical sectional view substantially along the line 1—1 of Fig. 2, looking in the direction indicated by the arrows, the cradle and car being shown in upright position; Fig. 2 is a side elevation of the same looking 105 toward the left of Fig. 1; Fig. 3 is an end 110

view partly in section with the cradle partially turned over; and Fig. 4 is a view looking toward the left of Fig. 3.

Referring now to the drawings, 10 represents the cradle containing a car 11 supported on a platen 12 which is movable in this instance to the right, as the same is viewed in Fig. 1, to bring the right hand side of the car against the supporting side 10 of the cradle, this being, of course, on the dumping side where the cradle is provided with a dumping apron 13 over which the coal slides or flows when the cradle is rotated, a cradle of this kind being adapted to be rotated through an arc of about 180° from normal position to dump the car and back again to normal position. The cradle is provided with end rings 14 which engage supporting rollers indicated at 15, and it is turned by motor driven pinions engaging arc-shaped rack segments 16. Any suitable car clamps 17 may be employed to hold the car on the cradle when the cradle is turned from normal position, which clamps are preferably actuated in the manner described in my patent and in my application aforesaid.

The coal when dumped from the cars is adapted to be received in suitable hoppers 18 beneath the cradle and slightly to one side of the center line thereof, as indicated in Figs. 1 and 3.

As previously stated, during the dumping operation and before the full dumping position is reached, the coal flows out of the car onto the apron plate 13, and in seeking its natural angle of repose it flows forwardly on the apron, as illustrated in Fig. 3, but as it flows in all directions in seeking its angle of repose, it also flows endwise of the cradle and out of the ends thereof when a car of substantially the length of the cradle is being dumped, particularly if the car is less than maximum height. This outward flow of coal from the ends of the cradle can not be entirely prevented by side plates permanently attached to the cradle at the ends of the apron, for obviously such plates if of sufficient height for this purpose would project into the cradle too far to permit cars of standard width to be run into the cradle.

Narrow side plates which do not interfere with the movement of the car into and out of the cradle are usually provided on the dumping side of these cradles, as shown at 13^a in Figs. 1, 3 and 4, these side plates being somewhat enlarged and tapered inwardly at the outer ends as shown at 13^b, but as before stated, they can not have sufficient depth or height to prevent the spillage of coal from the ends of the cradle.

To prevent the outflow of coal from the ends of the cradle, as just described, and also to have a more uniform distribution of coal in the hoppers than was possible here-

tofore, in accordance with the present embodiment of the invention I place in the apron plate adjacent its ends, and preferably, just inside of the rack segment 16, openings 19 which are so disposed and are of such a size that when the cradle is turned part way over, the coal which would otherwise spill out of the ends of the cradle passes through these openings into the hoppers 18, this occurring before the cradle has been turned to a position to cause the coal from the middle portion of the car to flow over the forward edge of the apron. In Figs. 3 and 4 I have shown the passage of this coal through these openings when the cradle has been given about half its dumping movement.

There is thus obtained a partial dumping of the coal when the cradle and car are part way turned over, or a preliminary dumping of a sufficient amount of the coal which was in the end portions of the car, to prevent the spillage from the ends of the cradle.

The coal which passes into the hoppers through the openings 19 while the cradle is being turned to dumping position, lodges in the bottom portions of the hoppers 18, and when the main body of the coal flows over the forward edge of the apron into the hoppers, the latter are filled substantially uniformly and the coal stands at practically uniform level from end to end, and the high piling of coal at the ends of the hoppers as heretofore experienced, is avoided. Therefore, the two disadvantages previously enumerated, are overcome, and in so doing I am enabled to use the shortest possible cradle for a car of given length and a hopper or a plurality of hoppers of less size and capacity than would otherwise be required.

In the drawings, I have shown only the preferred way of accomplishing the results, and I have illustrated openings whose size and location have been found suitable for given dumper installations operating under usual or normal conditions. However, in other installations it may be found desirable to vary the size, number, location, or shape of the openings, as for example, by extending them out to the outer edge of the apron plate, and furthermore, other ways of carrying out the principle of my invention may occur to one skilled in the art, and I therefore do not desire to be confined to the arrangements or details illustrated, but aim in my claims to cover all modifications which do not involve a departure from the spirit and scope of my invention as defined in the appended claims.

Having described my invention, I claim:

1. A car dumper having a rotary cradle adapted to receive a car, and an apron plate over which the material of the car is adapted to be passed in the dumping operation, said cradle being provided with means for caus-

ing a partial discharge of material from the car and cradle before the main body of the material passes over the forward edge of the apron.

5. A car dumper comprising a cradle adapted to be turned to dump the car's contents laterally, and means for discharging from the cradle the material located adjacent the ends of the car before the contents 10 of the middle portion of the car is discharged from the car and cradle.

3. A car dumper comprising a cradle adapted to receive a car and to be turned to dump the car's contents laterally, and 15 one or more hoppers beneath the cradle to receive the contents of the car, said cradle being provided with means for causing material from the end portions of the car to be first discharged into the hopper or 20 hoppers.

4. A car dumper comprising a cradle adapted to receive a car and to be turned about a longitudinal axis, and one or more

hoppers beneath the cradle to receive the contents of the car, said cradle being constructed to cause the bottom of the hopper or hoppers to be filled with material passing from the end portions of the car. 25

5. A car dumper comprising a cradle adapted to receive a car and to be turned 30 about a longitudinal axis, said cradle having an apron plate on the dumping side constructed to cause an earlier discharge of material from the end portions of the car than from the middle thereof.

6. A car dumper comprising a cradle adapted to receive a car and to be turned to dump the car's contents laterally, said cradle being provided with an apron plate provided adjacent its ends with openings to 40 permit material from the end portions of the car to pass from the cradle.

In testimony whereof, I hereunto affix my signature.

ARTHUR F. CASE.
